CONDENSER APPARATUS

Filed Nov. 26, 1943

This technical drawing illustrates a device assembly, likely a filter or a component of a larger system. The assembly includes several distinct parts:

- Fig. 4.:** A perspective view showing a central vertical structure (14) with a mesh or filter element (34) supported by a frame (35). A tube (18) is connected to the top of the structure. A support arm (36) is attached to the side, and a base (33) is shown at the bottom.
- III:** A side view of a U-shaped tube assembly (30) with a central vertical tube (12) extending downwards.
- Front View:** A large, irregularly shaped component featuring a grid of circular holes. It is labeled with the following numbers:
  - 11: A vertical rib or support on the left side.
  - 14: A vertical rib or support on the right side.
  - 18: A curved tube or duct leading into the main body.
  - 25: A circular opening or hole on the left side.
  - 33: A vertical rib or support on the right side.
  - 36: A vertical rib or support on the left side.
  - 37: A circular opening or hole near the top center.
  - 38: A vertical rib or support on the right side.
  - 39: A vertical rib or support on the left side.
  - 19: A vertical rib or support on the right side.

CONDENSER APPARATUS

Frank A. Meyer, Brookline, Pa., assignor to Westinghouse Electric & Manufacturing Company, East Pittsburgh, Pa., a corporation of Pennsylvania

Application November 26, 1943, Serial No. 511,799

4 Claims. (Cl. 257—43)

This invention relates to heat exchangers, more particularly to heat exchangers embodying a tube nest having a central untubed space for flow of air and noncondensable gases, and has for an object to provide means forming a passage extending radially through the nest from the periphery thereof to the central untubed space, without omitting any of the tubes of the nest.

Another object of the invention is to provide, in a heat exchanger having a tube nest including a central untubed space, means providing a radially-extending passage from the periphery of the tube nest to the central untubed space thereof without breaking the tube nest periphery.

A further object of the invention is to provide, in a condenser of the radial-flow type, means providing a vent passage from a deaerating hotwell associating with the condenser to the central air offtake passage, without breaking the tube nest.

These and other objects are effected by the invention as will be apparent from the following description and claims taken in connection with the accompanying drawing, forming a part of this application, in which:

Fig. 1 is a longitudinal sectional view through a condenser of the radial-flow type embodying the principles of the present invention;

Fig. 2 is a sectional view taken along the line II—II of Fig. 1, looking in the direction indicated by the arrows;

Fig. 3 is an enlarged, fragmentary, sectional view taken along the line III—III of Fig. 1, looking in the direction indicated by the arrows; and,

Fig. 4 is a horizontal, sectional view taken along the line IV—IV of Fig. 3, looking in the direction indicated by the arrows.

Referring now to the drawing more in detail, there is shown, at 10, a condenser of the radial-flow type and comprising a shell 11, having an exhaust steam inlet 12 at the top thereof and a condensate outlet 13 at the bottom thereof. A circumferentially-unbroken nest of tubes 14 extends longitudinally within the shell, the terminal portions of the tubes being supported by tube plates 15 and 16 at the ends of the shell, and the tubes being supported intermediate their ends by a plurality of intermediate tube sheets 18 and 19. Waterbox structures 20 and 21 are associated with the tube plates 15 and 16, respectively, and provide for flow of water through the tubes.

The tubes 14 are so arranged as to provide a central untubed portion 24 extending longitudinally of the tube nest, the intermediate tube sheets 18 and 19 being perforated at 25 and 26,

respectively, to provide for uninterrupted flow of air and noncondensable gases to the cold or inlet end of the tubes for discharge through the air offtake 27. A deaerating hotwell 30 is secured to the outside of the shell 11 in position to receive condensate discharged through the condensate outlet opening 13, this hotwell being of conventional construction and forming, in itself, no part of the present invention, the latter being concerned with the means, now to be described, for venting the hotwell to the central untubed space 24 of the tube nest.

An elongated channel-shaped member 33 has its longitudinal edges secured to the intermediate tube sheet 18 by suitable means, such as the weld deposits 34 and 35 (Fig. 4). The upper end of the passage 36, defined by the channel member 33 and the associated surface of the intermediate tube sheet 18, has its upper end 37 opening to the central untubed space 24 and its lower end 38 in communication with the interior of the hotwell 30 through suitable conduit means 39. Obviously, in installations or constructions where an intermediate tube sheet overlies the hotwell, the conduit 39 may be dispensed with and an opening provided through the shell for communication of the hotwell interior with the lower end of the passage 36.

Preferably, the channel-shaped member 33 is welded or otherwise secured to the surface of the intermediate tube sheet 18 after drilling of the tube-receiving openings in the latter. The channel-shaped member 33 is of sufficient rigidity to permit of drilling of tube-receiving openings through the channel structure as well as the tube sheet to which it is secured so that the tubes may pass directly through the side walls of the channel member 33 when the tube location happens to coincide therewith, as shown in Fig. 3.

The primary purpose and advantage of the invention herein disclosed lies in the fact that it is unnecessary to omit any of the tubes of the tube nest, as has heretofore been necessary when providing a passage extending radially of the tube nest. In other words, with prior practice, it would be necessary to omit all of the tubes enclosed within or intersecting the side walls of the channel member 33, as shown in Fig. 3.

While the invention has been shown in but one form, it will be obvious to those skilled in the art that it is not so limited, but is susceptible of various changes and modifications without departing from the spirit thereof, and it is desired, therefore, that only such limitations shall be

placed thereupon as are specifically set forth in the appended claims.

What is claimed is:

1. In heat exchange apparatus, a shell having a steam inlet at the top and a condensate outlet at the bottom; tube plates closing the ends of the shell; a nest of tubes extending longitudinally of the shell with their terminal portions carried by the tube plates; said tubes being arranged to provide a central untubed space for longitudinal flow of air and noncondensable gases to an air offtake; waterbox structure associated with the tube plates and providing for circulation of water through the tubes; one or more tube sheets supporting the tubes intermediate their ends; a hotwell adapted to receive condensate from the condensate outlet; and means for venting said hotwell to the central untubed space; said means comprising a channel-like member having its longitudinal edges joined to one surface of an intermediate tube sheet, whereby said tube sheet cooperates with the channel-like member to define a vertical passage, said passage being open at its upper end to the central untubed space, and means providing communication between the hotwell and the lower end of the passage.

2. Structure as specified in claim 1, wherein

some of the tubes of the nest pass through the vent passage.

3. Structure as specified in claim 1, wherein the normal tube layout is uninterrupted in the vicinity of the vent passage, with some of the tubes passing through said passage.

4. In a condenser, a shell having an exhaust steam inlet and a condensate outlet; tube plates closing the ends of the shell; a circumferentially-unbroken nest of tubes extending longitudinally of the shell with their terminal portions carried by the tube plates; said tubes being arranged to provide a central untubed space for longitudinal flow of air and noncondensable gases to an air offtake; a tube sheet supporting the tubes intermediate their ends; a deaerating hotwell adapted to receive condensate from the condensate outlet; and means for venting the hotwell to the central untubed space, said means comprising an elongated member of trough-like cross-section having its longitudinal edges secured to one surface of the intermediate tube sheet; said member and tube sheet defining a radial passage open at its inner end to the central untubed space, and means providing communication between the hotwell and the outer end of the radial passage.

FRANK A. MEYER.
